UNITED STATES PATENT OFFICE

KARL ERNST WENZEL, OF HAMBORN, GERMANY, ASSIGNOR, BY MESNE ASSIGNMENTS,
TO THE FIRM: VEREINIGTE EISENBAHN-SIGNALWERKE G. M. B. H., OF BERLIN-
SIEMENSSTADT, GERMANY

SAFETY CONTRIVANCE ON PERMANENT RAILWAY TRACKS

Application filed January 11, 1929, Serial No. 331,919, and in Germany February 9, 1928.

My Patent 1,683,709, dated September 11, 1928, relates to a safety contrivance on permanent railway tracks, in which a two-part insulated rail section and a relay comprising an armature and two windings or instead of the latter only one winding and two series resistances connected in parallel thereto, the two parts of said insulated rail sections being connected each to one of said windings or to one of said series resistances and adapted to be short circuited for an attraction of the relay armature by each two succeeding train wheel axles running over the same.

This construction is open to certain objections for indicating the arrival of a train on the first insulated section. In order to attain satisfactory signalling, it is necessary to provide a relay for each part of the two part insulated track so that two ordinary relays and one relay with two windings or two resistances are required.

This drawback is avoided according to the invention, by providing for each section of the insulated track an ordinary relay and by connecting the contacts of these two relays in such a manner that both relays remain energized or deenergized during the time the train occupies the second section in each direction of travel. It has already been proposed to subdivide the section block into two insulated sections, an electromagnet being connected to each section, and the two electromagnets being rendered mechanically dependent on each other.

The invention has for its object to make the attracting or the dropping of a relay dependent upon whether the insulated rail sections are occupied by a train or not and to eliminate all accidental causes in actuating the relay. For example, if the rails happen to be covered with coal, the train shunt on the rail is not effective to cause the track relay to become deenergized because of the high resistance of the shunt.

Two constructional forms of the invention are illustrated by way of example in the accompanying drawing, both in plan view.

In the form of construction shown in Fig. 1, the arrangement is such that when the train runs on the first insulated rail section i_1

this fact is at once indicated by illumination of the signalling lamp g provided for this purpose, while on the other hand the device m is operated only as the train passes on to the second insulated rail section i_2 and remains in operation so long as this section is occupied. This effect is obtained by the fact that the relay s_1 is connected permanently to the insulated rail section i_1 and the relay s_2 to the insulated rail section i_2 . At the relay s_1 the contacts k_1 , k_2 and k_5 , and at the relay s_2 the contacts k_2 , k_4 and k_6 are closed, when the relays are energized. If a train runs over the insulated rail section i_1 the closing of the contacts k_1 and k_5 are ineffective, but by the contact k_3 the signalling lamp g or any other signalling device is operated. When the train runs over the insulated rail section i_2 the two relays are connected in parallel with one another over the contacts k_1 and k_2 in series so that the relay s_1 remains attracted like relay s_2 , when the insulated rail section i_1 has become free. The contact k_6 closes the circuit over contact k_5 to the operating magnet m , so that the latter, as wanted, becomes energized while a train runs over the insulated rail section i_2 . The contact k_4 is connected in parallel to contact k_3 and the former is only necessary for the purpose of operating the signalling lamp g , when the train runs in opposite direction, i. e. from the insulated rail section i_2 to the insulated rail section i_1 .

In the form of construction shown in Fig. 2 the operation of the device shown in Fig. 1 is made better by the fact that the both relays s_1 and s_2 are normally connected in closed circuit over the insulating rail sections i_1 and i_2 , so that they are short circuited by the axles of the train. One is then less dependent on the resistance of the insulated rail sections. For a careful treatment of the battery the resistances w_1 and w_2 are connected in series with the relay-windings. The relay-contacts k_1 and k_2 serve for the same purpose as in Fig. 1 but only with the difference that they are not closed when the armatures of the relays are attracted but when they are dropped. This is obtained by the fact that in the arrangement according to Fig. 2 the operation

of the relays takes place not by closing of the current to the relays but by short-circuiting of the relays.

What I claim, is:

- 5 1. A device for releasing, operating and locking safety contrivances on railway tracks, comprising in combination with a two section insulated track, a relay for each section of said insulated track, and two contacts for
10 each of said relays mutually connected so that they cause said relays to remain operative as long as a train is on one of the two sections of said insulated track by the passage of the train from the other section.
- 15 2. A device as specified in claim 1, comprising in combination, the contrivance to be secured, the signalling and locking device and the two relays with two contacts connected to the insulated rail sections, two relay contacts adapted to be series connected for switching in said contrivance only when a train has passed from one section into the other section, and two relay contacts adapted to be parallel connected for operating said signalling or locking device when a train is
20 in either section.
- 25 3. A device as specified in claim 1, comprising in combination with the contrivance to be secured, the signalling and locking device and the two relays, two contacts connected to the insulated rail sections, two relay contacts adapted to be series connected for switching in said contrivance only when a train has passed from one section into the other section, and two relay contacts adapted to be parallel connected for operating said signalling or locking device when a train is
30 in either section and two resistances for connecting said two relays in a closed circuit
35 through said insulated rail sections, and armatures of said relays adapted to operate said contacts in dropping.
- 40 4. In testimony whereof I have hereunto set my hand.
